MACHINE FOR TARGET PRACTICE

Curtis A. Anderson, Mamaroneck, N. Y.

Application January 26, 1946, Serial No. 643,611

17 Claims. (Cl. 273—101.2)

1

My invention relates to machines for target practice and has particular reference to machines in which a moving target is provided for an operator to exercise his skill in correctly aiming at the same.

My invention has for its object to provide a machine of the foregoing general character in which a moving target is provided to be viewed by an operator in an observation window, and further means are provided for the operator to place an imitation gun sight in line with the target and to simulate shots at the target.

A further object of my invention is to provide means in the machine for recording the shots and also for recording the hits, i. e. shots made at the exact moments when the target is exactly in line with the gunsight.

I prefer to provide my machine with a movable stick to be manipulated in a manner similar to the manipulation of a control stick on an airplane, conditions being thereby created similar to the conditions in which a pilot of a fighting plane maneuvers his airplane to obtain a sight on the enemy plane.

An allied object of my invention is to provide means to render the machine operative by dropping a coin in a coin slot, and to limit the time of operation of the machine by a predetermined length of time, at the expiration of which the machine will stop until a new coin is deposited.

The foregoing and other objects, features and advantages of my invention are more fully explained in the following specification and accompanying drawing in which:

Fig. 1 is a sectional elevational view of the machine in which a photocell is employed for registering hits;

Fig. 2 is a front view of the same partly in section taken on the line 2—2 of Fig. 1;

Fig. 3 is a top plan view partly in section taken on the line 3—3 of Fig. 1;

Fig. 4 is a detail view of a motor operated mirror;

Fig. 5 is a diagrammatic view of electrical connections and wiring used in my machine;

Fig. 6 is a sectional elevational view of a modified machine without the photocell;

Fig. 7 is a detail view of the manually operable mechanism for moving the projector;

Fig. 8 is a fractional diagrammatic view of the electrical connections for Fig. 6.

My machine in a form shown in Figs. 1 to 5 inclusive comprises a housing 1 having a front extension 2 of a reduced height. A screen 3 in the shape of a disc 3 made of frosted glass or similar

2

translucent material, preferably of a convex shape, is placed in a window 4 in the front wall 5 of the housing 1. A miniature image of a flying object such as an airplane 8 is projected on the screen 3 by a suitable projector 9 of a conventional type through two mirrors 10, 11 as shown in dotted lines 12. The upper mirror 11 is continuously moved in all directions, causing the image 8 to be moved all over the screen. The mirror 11 for this purpose is mounted on a universal ball and socket type bearing as shown in Figs. 1 and 4, consisting of a ball 14 extending from the rear side of the mirror, rotatively supported in a round socket 15. The latter is supported on legs 16 mounted on the rear wall of the housing. The mirror is moved on its bearing in all directions by an electric motor 17 with a suitable speed reducer through cams 20, 21. Cam 20 is connected to the motor by a shaft 19 and engages a roller 22 rotatively supported in a bracket 23 mounted on the rear side of the mirror. The second cam 21 is mounted on a shaft 24 rotatively supported in a bearing 25 in one of the legs 16 and connected by bevel gears 26 with the shaft 19. The second cam 21 engages a roller 27 rotating in a bracket 28 mounted on the under side of the mirror. The cams 20, 21 are provided with a plurality of lobes and depressions for causing the mirror to oscillate in an irregular manner. A spring 30 is provided for urging the mirror toward the rollers.

For bringing the image 8 into the center of the screen where hairlines 31 intersect each other, a manually operated mechanism is provided for moving the mirror 10 in different directions so as to counteract the displacements of the image caused by the operation of the cams 20, 21. Mirror 10 is also mounted on a ball and socket type bearing, being provided with a ball-shaped projection 32 at the under side rotatively supported in a round socket 33 which is in turn supported on legs 34 mounted on the base 35 of the housing. The ball-shaped projection 32 is provided with a depending rod 36 pivotally connected at 38 to one end of a rod 39 whose other end is pivotally connected at 40 to the lower end of an operating stick 42. The latter is provided with a ball 43 at its intermediate portion rotating in a bearing 44 supported on legs 45 mounted on the base 35. The upper portion of the stick 42 extends through a large hole 46 in the upper wall 47 of the extension 2 and is provided with a suitable handle 48 for its manipulation. By rocking the stick 42 back and forth, the mirror is made to be rotated in a vertical plane. For its rotation

in another vertical plane at right angles to the first plane, the lower end portion of the stick is placed in a fork-shaped end portion 50 of a second rod 51 rotatively supported in its intermediate portion on a pivot 52. The other end of the second rod 51 is provided with a similar fork 53 engaging the lower portion of the rod 36. Thus, by rocking the stick 42 from side to side, the mirror 10 is caused to rotate in a second vertical plane at right angles to the first plane. By suitably moving the stick 42 in all directions, the movements of the upper mirror 11 can be compensated for maintaining the image 8 exactly in the center of the screen 3.

The machine is provided with a coin actuated switch for starting operation of the motor 17. A second motor operated switch is also provided for limiting the operation of the machine to a predetermined length of time such as one minute, for instance. A coin slide 55 is provided for this purpose with a coin slot 56. The slide can be manually moved for dropping the coin into a coin box 57. A door 58 is provided with a lock for removing the coins. A switch 58 (Fig. 5) of a conventional or other construction is provided for starting operation of the motor 17. The coin mechanism may be also of a conventional or other construction and is shown only diagrammatically in Fig. 1.

During operation of the machine, the operator can at any moment "shoot" at the target 8 by depressing a trigger or button 60 on the stick 42. The button closes a circuit, described more fully hereinbelow, for starting operation of the second or timing motor 61 (Fig. 5) and of a buzzer 62 for producing a sound effect to indicate that the target is being shot at. The second motor 61 operates a needle 63 of an indicator 64 for indicating the number of shots expended. A second indicator 65 is provided with a needle 66 operated by a third motor 70 for registering actual hits at the target. Such hits occur only when the image 8 is brought exactly into the center of the screen 3 at the point of intersection of the hair-lines 31, and when the trigger 60 is depressed. Motor 70 is then energized by a circuit including a photocell 71 in the center of the screen 3. The photocell is made conductive when the beam of light 12 is directed against it, closing a circuit for a relay 72 which in turn closes the circuit for the motor 70, causing the indicator 65 to register actual "hits."

Electrical connections are shown in Fig. 5. Electric current is taken from a source of supply 75 which may be alternating current or direct current and is shown as an alternating current. One terminal 76 of the source is connected by leads 77, 78 with one terminal of the motor 17, the other terminal of the motor 17 being connected by leads 79, 80 through the coin operated switch 59 with the other terminal 81 of the source of current. The switch 59 is closed for a short time by the coin, sufficient for starting the motor rotation, whereby a holding circuit for the motor is closed by a motor operated switch 82. The latter comprises a disc 82 operatively connected to the motor and provided with diametrically opposite projections 84, 85, normally acting on switch arms 86, 87 for separating them from contacts 88, 89. The arms 86, 87 are resilient and tend to engage the arms 88, 89 respectively. The projections 84, 85 leave the arms 86, 87 as soon as the motor starts rotation by temporarily closing the coin switch 59, thereby causing the contact arms 86, 88 to be closed, as well as the con-

tact arms 87, 89. The arm 88 is connected by leads 90, 91 and 79 with one terminal of the motor 17, and the control arm 86 is connected by a lead 92 with the lead 80. As a result, the motor will continue rotation, being energized by a holding circuit which may be traced as follows: from the supply lead 77 by the lead 78, motor 17, leads 79, 80, contact arms 88, 86 and lead 92 to the other supply lead 80. The motor will continue its rotation until the disc 82 makes one revolution when the projections 84, 85 will again separate the contact arms 88, 86, deenergizing the motor until another coin is deposited in the slot.

The projections 84, 85 also operate a contact arm 95 which is resiliently urged into engagement with a contact arm 96 and is separated therefrom by one of the projections 84, 85 (the arm 95 is shown in Fig. 5 at a distance from the projection 84, it being understood that the projection 84 acts simultaneously on both arms 86 and 95). The arm 96 is connected by a lead 97 with the lead 91, and the arm 95 is connected by leads 98, 99 and switch 60 with a contact arm 100 engageable with a resilient contact arm 101 connected by a lead 102 to a lead 103 extending to the coin switch 59. The arm 101 is held separated from the arm 100 by a projection 104 on a cam-shaped disc 105 operatively connected to the motor 61. The motor 61 is started momentarily by closing the coin switch 59, the circuit being closed as follows: from the supply line 83 by the switch 59, lead 103, motor 61, and a lead 106 to the other supply line 77. The motor, however, is immediately stopped as soon as the switch 59 is again opened, leaving, however, the contact arm 101 engaging the arm 100, thereby establishing a new circuit for the motor 61 through the trigger switch 60, as follows: from the supply line 77 by the lead 106, motor 61, leads 103, 102, contact arms 101, 100, lead 99, trigger switch 60, lead 98, closed contact arms 95, 96, leads 97, 91, 90, closed contact arms 88, 86, and lead 92 to the other supply lead 80.

Thus the operator, whenever he succeeds in placing the target 8 in the center of the screen 3, can start "shooting" by depressing the trigger switch 60 thereby energizing the motor for rotation, the successive "shots" being registered on the dial 64, it being assumed that each division of the dial corresponds to one "shot." At the same time the buzzer 62 will operate, creating a sound effect to indicate the shots. The buzzer is connected to the terminals of the secondary 110 of a transformer 111. A signal lamp 112 may be also connected across the secondary 110 to indicate that the "shooting" takes place. The primary 113 of the transformer 111 is connected at one end by a lead 114 to the lead 102 and at the other end by a lead 115 to a lead 116 extending to the contact arm 87, which now engages the other contact arm 89 connected by a lead 117 to the lead 78. Hence the buzzer can operate only when the main motor 17 is operating and when the trigger switch 60 is depressed. The operation of the main motor is indicated by a signal lamp 118 connected by 119, 120 with the leads 91 and 78, respectively.

No "shots" will be recorded on the indicator 65 as "hits," however, unless at the time of the "shooting" the target 8 is placed in the center of the screen 3. The indicating needle or pointer 66 is operated by the motor 70 one terminal of which is connected with the lead 77, and the other terminal of which is connected by a lead 124 with a contact 125 engageable by an ar-

ture 126 of the relay 12. The relay is connected by leads 127, 128 with an amplifier 129 for the photocell 71, which is connected with supply leads 91 and 137. The armature is connected by a lead 121 with the lead 98 through the triple trigger switch 60. Hence the motor 70 operates only when the relay 12 is energized and attracts the armature 126, the motor circuit being as follows: from the supply line 77 to the one terminal of the motor 70, through the motor, from the other terminal by the lead 124, contact 125, armature 126, lead 121, trigger switch 60, lead 98, closed contact arms 95, 96, leads 97, 94, 90, closed contact arms 88, 86, and lead 92 to the other supply line 80. "Hits" are indicated also by a bell 142 connected to the secondary of a transformer 143, the primary being connected at one end by a lead 144 to the lead 124 and at the other end by the lead 116 to the contact arm 87. An arrangement is also provided for causing the motors 61 and 70 to continue their rotation when the main motor has stopped and disconnected the circuits for the trigger switch 60 and photocell 71. The motor 70 is provided for this purpose with a switch comprising contact arms 130, 131, the resilient arm 131 being urged into a contact with the arm 130 and separated from the latter by a projection 132 on a cam-shaped disc 133 operated by the motor 70. The arm 130 is connected by a lead 134 with the lead 124, and the arm 131 is connected by a lead 135 with a contact 136 engaged by the resilient contact arm 86 when the latter is deflected by the projection 84 of the disc 82. A similar switch is provided at the motor 61 consisting of contact arms 138, 139 connected with leads 103 and 135, respectively, the resilient arm 139 being engageable by a projection 140 on the disc 105.

It may be seen that if the disc 82 engages the arms 86 and 87, breaking the operating circuits and stopping the main motor 70, and if the discs 105 and 133 have not yet completed their cycles of rotation so that the contact arms 138, 139 are closed as well as the contact arms 130, 131 then the motors 61, 70 will be energized by independent circuits which can be traced as follows: from the supply line 77 to the motor 70, then through lead 134, closed contact arms 130, 131, lead 135, contact 136, arm 86, and lead 92 to the other supply lead 80. Motor 70 will, therefore, continue its rotation until the contact arms 130, 131 are separated by the projection 132 or 132'. The bell 142 does not ring, however, during this additional rotation since its circuit is disconnected by the projection 85 which now separates the arms 87, 88. The motor 61 may still continue its rotation, however, if the projection 105 has not yet reached the contact arms 138, 139, which will remain therefore closed. The motor circuit can be traced as follows: from the supply line 77 by the lead 106, motor 61, lead 108', closed contact arms 138, 139, lead 135, closed contact 136 and arm 86, and lead 92 to the other supply line 80. The motor 61 will then complete its rotation until the projection 140 or 104 separates the arms 138, 139.

It may be noted that each needle or pointer 63 and 66 completes but one-half revolution for its complete cycle so that one or the other end of the pointers or needles is alternately used for indicating units on the scales 64, 65, the lower half of each scale being covered and invisible as shown in Fig. 2. The units of the scales 64, 65 correspond to certain time elements but they may be calibrated to indicate the number of "shots" on the scale 64 and successful "hits" on the scale 75

65. Lamps 112, 141 are so arranged as to render the scales 64, 65 visible only when the pointers 63, 66 are moving.

A modified machine is shown in Figs. 6, 7 and 8. The projector and the motor are mounted in a common elongated casing 150 in the upper portion of the housing 1 so that the beam 12 is directed on the screen 3 without the use of any mirrors. The casing 150 is mounted for rotation in a horizontal plane, being provided with vertical trunnions 151, 151' rotatively supported in a gimbal ring 153. The latter is provided with horizontal trunnions 154, 154' rotatively supported in a yoke 155 mounted on a base 156. The base 156 is rotatively mounted at 162 in a yoke 161 which is mounted at the upper end of a rod 160. The rod 160 is rotatively supported in brackets 163, 164 extending from the rear wall of the housing 1. The lower end of the rod 160 is provided with an arm 173, the distal end of the arm being pivoted at 174 to the rear end of a rod 175. The front end of the rod 175 is forked at 40, engaging the lower portion of the stick 42. The intermediate portion of the rod 175 is pivoted at 52 on a post 52'. Thus by moving the stick 42 from side to side, the rod 160 can be rotated on its axis together with the projector casing 150.

For rotating the base 156 in a vertical plane, a second rod 146 is provided slidably supported in the brackets 163, 164 and spaced from the rod 160. The upper end of the rod 146 is provided with a ball 141 engaging the base 156. The lower end of the rod 146 is provided with a roller 165 resting on a tapering or wedge-shaped block 166 slidably resting on the base 35 of the housing 1. A spring 147 urges the base 156 against the ball 141.

A spring 170 urges the rod 146 against the block 166. The block 166 can be moved by a bar 171 having a central opening 169 straddling the post 52'. The front end of the bar 171 is pivoted at 50 to the lower end of the operating stick 42. The rear end of the bar 171 is secured to the block 166 for moving the same back and forth when the stick 42 is moved forward or rearward, thereby raising or lowering the rod 146 and rotating the base 156 in a vertical plane.

It should be noted that other suitable connections may be employed between the stick 42 and the rod 160 for causing rotation of the rod and its axial movement.

For oscillating the beam 12 in different directions, the motor in the casing 150 is operatively connected to a cam 180 resting on a pair of rollers 181, 182 rotatively supported in brackets 183 on the base 156. A spring 184 urges the casing 150 towards the base 156 thereby also urging the cam into engagement with the rollers. The lobes and recesses on the cam 180 are so arranged that the casing 150 is caused to oscillate irregularly both in a horizontal and vertical plane. Current for the motor and projector in the casing 150 is supplied by flexible leads 188, 189. The casing is also provided with a contact 190 which engages a stationary contactor 191 when the beam 12 is directed into the center of the screen 3. The contact 190 is connected by a flexible lead 192 to the lead 137, and the contactor 191 is connected by a lead 193 to one end of the relay coil 72, the other end of the coil 72 being connected to the lead 91.

The operation of the machine shown in Figs. 6, 7, and 8 is similar to the operation of the machine shown in Fig. 1.

It will be understood that various features and principles of each of the embodiments of the invention above described or referred to may be utilized or substituted in the other embodiments.

While the invention has been described in detail with respect to certain particular preferred examples, it will be understood by those skilled in the art after understanding the invention, that various changes and further modifications may be made without departing from the spirit and scope of the invention, and it is intended therefore in the appended claims to cover all such changes and modifications.

What is claimed as new and desired to be secured by Letters Patent is:

1. A target practicing machine comprising a housing; a translucent screen therein; means in the housing to project an image of a target on the screen; a motor in the housing; means operated by the motor for causing the projected image of the target to be moved away from the center of the screen in different directions; a member including a switch movably supported in front of the housing adapted to be moved by an operator; means operated by the member for causing the projected image to be moved in different directions so as to bring the image into a predetermined position on the screen; and signal means responsive to actuation of said switch to indicate the moments when the image is brought into said predetermined position.

2. A target practicing machine comprising a housing; a translucent screen forming a portion of the front wall of the housing; means in the housing to project an image of a target on the screen; a motor in the housing; means operated by the motor for causing the projected image of the target to be moved away from the center of the screen in different directions; a member including a switch movably supported in front of the housing adapted to be moved by an operator; means operated by the member for causing the projected image to be moved in different directions so as to bring the image into a predetermined position on the screen; signal means responsive to actuation of said switch to indicate the moments when the image is brought into said predetermined position; and means to limit the length of time when the motor is operated.

3. A target practicing machine comprising a housing; a translucent screen forming a portion of the front wall of the housing; means in the housing to project an image of a target on the screen; a motor in the housing; means operated by the motor for causing the projected image of the target to be moved away from the center of the screen in different directions; a member including a switch movably supported in front of the housing adapted to be moved by an operator; means operated by the member for causing the projected image to be moved in different directions so as to bring the image into a predetermined position on the screen; a coin operated switch for initially energizing the motor; a cam-shaped member operatively connected to the motor; switch means operated by the cam-shaped member for maintaining the motor energized for a predetermined length of time; and signal means responsive to actuation of said switch to indicate the moments when the image is brought into said predetermined position.

4. A target practicing machine comprising a housing; a translucent screen forming a portion of the front wall of the housing; means in the housing to project an image of a target on the

screen; a motor in the housing; means operated by the motor for causing the projected image of the target to be moved away from the center of the screen in different directions; a member including a switch movably supported in front of the housing adapted to be moved by an operator; means operated by the member for causing the projected image to be moved in different directions so as to bring the image into a predetermined position on the screen; a coin-operated switch for initially energizing the motor; a cam-shaped member operatively connected to the motor; switch means operated by the cam-shaped member for maintaining the motor energized for a predetermined length of time; signal means responsive to actuation of said switch to indicate the moments when the image is brought into said predetermined position; and means to render the signal means inoperative after the motor is deenergized.

5. A target practicing machine comprising a housing; a translucent screen forming a portion of the front wall of the housing; means in the housing to project an image of a target on the screen; a motor in the housing; means operated by the motor for causing the projected image of the target to be moved away from the center of the screen in different directions; a member movably supported in front of the housing adapted to be moved by an operator; means operated by the member for causing the projected image to be moved in different directions so as to bring the image into a predetermined position on the screen; signal means to indicate the movements when the image is brought into said predetermined position; and a manually operable trigger switch in said member for rendering the signal means operative.

6. A target practicing machine comprising a housing; a translucent screen forming a portion of the front wall of the housing; means in the housing to project an image of a target on the screen; a motor in the housing; means operated by the motor for causing the projected image of the target to be moved away from the center of the screen in different directions; a member movably supported in front of the housing adapted to be moved by an operator; means operated by the member for causing the projected image to be moved in different directions so as to bring the image into a predetermined position on the screen; signal means to indicate the moments when the image is brought into said predetermined position; a manually operable trigger switch for rendering the signal means operative; and means to indicate periods when the trigger switch is operated.

7. A target practicing machine comprising a housing; a translucent screen forming a portion of the front wall of the housing; means in the housing to project an image of a target on the screen; a motor in the housing; means operated by the motor for causing the projected image of the target to be moved away from the center of the screen in different directions; a member movably supported in front of the housing adapted to be moved by an operator; means operated by the member for causing the projected image to be moved in different directions so as to bring the image into a predetermined position on the screen; a trigger switch; an indicator calibrated in units of time; a rotary pointer in the indicator; means to cause the pointer to rotate in response to the operation of the trigger switch for indicating the number of units of time when the trig-

ger switch is operated; a second indicator calibrated in units of time; a pointer in the second indicator; and means to cause the pointer to advance on the scale in response to the trigger switch being operated and the projected image being centered at a predetermined point on the screen thereby indicating on the second indicator the number of units of time when the image is centered simultaneously with the operation of the trigger switch.

8. A target practicing machine comprising a housing; a translucent screen forming a portion of the front wall of the housing; means in the housing to project an image of a target on the screen; a motor in the housing; means operated by the motor for causing the projected image of the target to be moved away from the center of the screen in different directions; a member movably supported in front of the housing adapted to be moved by an operator; means operated by the member for causing the projected image to be moved in different directions so as to bring the image into a predetermined position on the screen; a trigger switch; an indicator calibrated in units of time; a rotary pointer in the indicator; means to cause the pointer to rotate in response to the operation of the trigger switch for indicating the number of units of time when the trigger switch is operated; a second indicator calibrated in units of time; a pointer in the second indicator; means to cause the pointer to advance on the scale in response to the trigger switch being operated and the projected image being centered at a predetermined point on the screen thereby indicating on the second indicator the number of units of time when the image is centered simultaneously with the operation of the trigger switch; means to limit the length of time when the motor is operated; and means to render the indicators inoperative after the motor is de-energized.

9. A target practicing machine comprising a housing; a translucent screen forming a portion of the front wall of the housing; means in the housing to project an image of a target on the screen; a motor in the housing; means operated by the motor for causing the projected image of the target to be moved away from the center of the screen in different directions; a member movably supported in front of the housing adapted to be moved by an operator; means operated by the member for causing the projected image to be moved in different directions so as to bring the image into a predetermined position on the screen; a trigger switch; a second motor connected in a circuit with the trigger switch; an indicator having a pointer operated by the second motor and having a scale calibrated in "shots" or number of time units when the trigger switch is operated; a third motor connected in a circuit with the trigger switch; switch means included in the circuit of the third motor and arranged to close the circuit in response to the image being brought into the predetermined position on the screen; and a second indicator having a pointer operated by the third motor and having a scale calibrated in "hits" or units of time when the trigger switch is operated simultaneously with the switch means.

10. A target practicing machine comprising a housing; a translucent screen forming a portion of the front wall of the housing; means in the housing to project an image of a target on the screen; a motor in the housing; means operated by the motor for causing the projected image of

the target to be moved away from the center of the screen in different directions; a member movably supported in front of the housing adapted to be moved by an operator; means operated by the member for causing the projected image to be moved in different directions so as to bring the image into a predetermined position on the screen; a trigger switch; a second motor connected in a circuit with the trigger switch; switch means included in the circuit of the second motor and having a scale calibrated in "shots" or number of time units when the trigger switch is operated; a third motor connected in a circuit with the trigger switch; switch means included in the circuit of the third motor and arranged to close the circuit in response to the image being brought into the predetermined position on the screen; a second indicator having a pointer operated by the third motor and having a scale calibrated in "hits" or units of time when the trigger switch is operated simultaneously with the switch means; means operated by the first motor for limiting the length of time of the first motor's operation; and means to render the second and the third motors inoperative after the first motor is stopped.

11. A target practicing machine comprising a housing; a translucent screen forming a portion of the front wall of the housing; means in the housing to project an image of a target on the screen; a motor in the housing; means operated by the motor for causing the projected image of the target to be moved away from the center of the screen in different directions; a member movably supported in front of the housing adapted to be moved by an operator; means operated by the member for causing the projected image to be moved in different directions so as to bring the image into a predetermined position on the screen; a trigger switch; a second motor connected in a circuit with the trigger switch; an indicator having a pointer operated by the second motor and having a scale calibrated in "shots" or number of time units when the trigger switch is operated; a third motor connected in a circuit with the trigger switch; switch means included in the circuit of the third motor and arranged to close the circuit in response to the image being brought into the predetermined position on the screen; a second indicator having a pointer operated by the third motor and having a scale calibrated in "hits" or units of time when the trigger switch is operated simultaneously with the switch means; means operated by the first motor for limiting the length of time of the first motor's operation; means to render the second and the third motors inoperative after the first motor is stopped; and means responsive to said preceding means to cause the second and third motors to bring the respective indicator pointers to zero positions.

12. A target practicing machine comprising a housing; a translucent screen forming a portion of the front wall of the housing; means in the housing to project an image of a target on the screen; a motor in the housing; means operated by the motor for causing the projected image of the target to be moved away from the center of the screen in different directions; a member movably supported in front of the housing adapted to be moved by an operator; means operated by the member for causing the projected image to be moved in different directions so as to bring the image into a predetermined position on the screen; a trigger switch; a second motor

11

connected in a circuit with the trigger switch; an indicator having a pointer operated by the second motor and having a scale calibrated in "shots" or number of time units when the trigger switch is operated; a third motor connected in a circuit with the trigger switch; switch means included in the circuit of the third motor and arranged to close the circuit in response to the image being brought into the predetermined position on the screen; a second indicator having a pointer operated by the third motor and having a scale calibrated in "hits" or units of time when the trigger switch is operated simultaneously with the switch means; means operated by the first motor for limiting the length of time of the first motor's operation; means to render the second and the third motors inoperative after the first motor is stopped; means responsive to said preceding means to cause the second and third motors to bring the respective indicator pointers to zero positions; and means to render the indicator scales visible when their pointers are being moved by the second and third motors.

13. A target practicing machine as set forth in claim 9 in which the switch means in the circuit of the third motor is controlled by a photoelectric element.

14. A target practicing machine comprising a screen; a projector for projecting an image of a target on the screen; a motor; cam means operated by the motor for moving the projector, whereby the target image is moved in different directions away from a predetermined point on the screen; manually operable means including a trigger switch for independently moving the projector in different directions; and signal means responsive to actuation of said switch to indicate the moments when the image is brought by the manual means into the predetermined position on the screen.

15. A target practicing machine comprising a screen; a projector for projecting an image of a target on the screen; a motor; cam means operated by the motor for moving the projector, whereby the target image is moved in different directions away from a predetermined point on the screen; manually operable means including a trigger switch for independently moving the projector in different directions; signal means responsive to actuation of said switch to indicate

12

the moments when the image is brought by the manual means into the predetermined position on the screen; and means to count the number of units of time when the image is brought into the predetermined position.

- 5 16. A target practicing machine comprising a screen; a projector for projecting an image of a target on the screen; a motor; cam means operated by the motor for moving the projector, whereby the target image is moved in different directions away from a predetermined point on the screen; manually operable means for independently moving the projector in different directions; signal means to indicate the moments 10 15 when the image is brought by the manual means into the predetermined position on the screen; means to count the number of units of time when the image is brought into the predetermined position; and manually operable trigger means for 20 rendering the signal means and the counting means operative.

17. A target practicing machine comprising a screen; a projector for projecting an image of a target on the screen; a motor; cam means operated by the motor for moving the projector, whereby the target image is moved in different directions away from a predetermined point on the screen; manually operable means for independently moving the projector in different directions; signal means to indicate the moments 25 30 when the image is brought by the manual means into the predetermined position on the screen; an indicator having a rotary element for indicating the total number of units of time when the 35 40 image is brought into the predetermined position; means responsive to the position of the projector when the image is projected on the predetermined point on the screen for causing rotation of the indicator element; and trigger means to render the indicator element rotating means operative.

CURTIS A. ANDERSON.
